MECHANICALLY OPERATING CONTINUOUS SPEED VARIATOR

Lino Gubbiotti, Perugia, Italy, assignor to Società Variatori Gubbiotti S.r.l., Perugia, Italy, a company of Italy

Filed Dec. 2, 1960, Ser. No. 73,250

Claims priority, application Italy Jan. 11, 1960
4 Claims. (Cl. 74—112)

The present invention relates to a continuous speed variator.

The purpose of this invention is to provide a continuous speed variator the operation of which is exclusively mechanical, in order to obtain an efficiency far higher than that obtainable by hydraulic variators.

Another purpose of this invention is to provide a variator of the cited kind, suitable to be mounted either on industrial machines or to be used with the drive of vehicles. In the latter case, the variator according to this invention makes it possible to dispense with the friction clutch and the differential.

According to this invention, a unit is provided comprising, in combination, an input shaft to which the motive power is applied, a cylindrical drum rigid with said shaft and internally provided with a circular cross-section eccentric recess, a sleeve received in the recess, and also provided with an eccentric recess the eccentricity of which is equal to that of the cylindrical, a further sleeve having an annular cross-section mounted in said cylindrical recess of said first-mentioned sleeve, an output shaft received in said further sleeve, and provided with cross-seatings, means allowing said further sleeve to make translational movements, but preventing said sleeve from rotating about its axis, thrust elements mounted in said seatings to transmit the movement of said annular cross-section sleeve to the output shaft, and means for changing at will the relative position of the two eccentric recess cylinders and therefore the drive ratio.

This invention will be hereinafter described with reference to the attached drawings showing an embodiment of the invention, only by way of example:

In the drawings:

FIG. 1 is a side view of the variator partially in cross-section and taken along a vertical plane;

FIG. 2 is a cross-sectional view taken along the plane II—II of FIG. 1;

FIG. 3 is a cross-sectional view taken along the plane III—III of FIG. 1;

FIG. 4 is a partial cross-sectional view taken along the line IV—IV of FIG. 1;

FIG. 5 is a cross-sectional view taken along the plane V—V of FIG. 4;

FIG. 6 is a cross-sectional view taken along the plane VI—VI of FIG. 3;

FIG. 7 is a side view of the output shaft, partially in cross-section and taken along an axial longitudinal plane;

FIGS. 7A, 7B, 7C, 7D, 7E show, in the cited order, the cross-sectional views corresponding to the planes A—A, B—B, C—C, D—D and E—E, respectively;

FIG. 8 shows the detail, on an enlarged scale, one of the thrust elements;

FIG. 9 is a side view of the detail of FIG. 8, and

FIG. 10 is a cross-sectional view taken along the plane X—X of FIG. 9.

With reference to FIGS. 1 to 3, the input shaft 1 is connected to a prime mover of any type, not shown.

The shaft 1 is journaled in a roller bearing 2 supported by a case 3 provided with a bed plate 4, and terminates in a flange 5 to which, by means of a set of screws 6, is fixed a first cylindrical drum 7 internally provided with a circular cross-section eccentric bore 8.

2

Within said bore 8 is rotatably mounted a second cylindrical drum 9, which is also provided with an internal eccentric bore 10 into which a tubular sleeve 11 is inserted.

The drum 9 and the sleeve 11 are immersed in an oil bath, the oil for which is fed into the drum 7 through an aperture closed by means of the screw 16.

The front portion of the drum 7 is connected to the collar 12 which in turn is rotatably mounted on the hollow hub 14 by means of the roller bearing 13. Between said two elements a seal ring 15 is inserted having the function of preventing the lubricating oil from escaping. The hollow hub 14, in turn is fixed rigidly by a lock screw 17 to a cap 18 which is fastened to the case 3 by the bolts 19. A roller bearing 20 is mounted between the hollow hub 14 and the cap 18, and said roller bearing, in the conditions shown in FIG. 1 is inoperative because of the lock screw 17 fixing the hub 14 rigid with the case 3, as aforesaid.

The tubular sleeve 11 is fixed by the screws 21 to a bushing 22 forming part of a double slider coupling (shown also in FIGS. 4 and 5) which bushing is provided with two front dogs 23 on diametrically opposite sides of the axis of sleeve 11. Two other front dogs 24 on the opposite ends of a diameter at 90° to the alignment of dogs 23 are carried by the hollow hub 14 forming a second part of the coupling (FIG. 5). Said pairs of front dogs, enter corresponding notches 25 of a ring 26, which forms the third part of the coupling, and having the function of preventing the tubular sleeve 11 from rotating about its axis, although allowing a limited transverse translation movement of said sleeve.

Concentrically with the hub 14 (FIG. 1) is mounted the output shaft generally denoted at 27 to which the resistant torque is applied. The output shaft 27 is supported by the pair of ball bearings 28 spaced apart by the spacer 29, and by the bearing 30 mounted at the inner end of the shaft, near the flange 5. A set of transverse seats 31 (FIGS. 7 to 7E) parallel to one another is provided in the shaft 27 and said seats are equiangularly spaced

around the output shaft. In the illustrated example, there are five seats 31 angularly spaced from each other by 72°. In each transverse seat 31 is positioned a thrust element generally denoted at 32, said thrust element being shown in detail in FIGS. 8 to 10. Each element 32 has a length slightly less than the diameter of the inner periphery 33 of the tubular sleeve 11 and the ends of said element 32 are shaped to match the contour of the inner periphery 33. The body 32 of the thrust element is provided with an inner groove 34 wherein is received a set of rollers 35 on which rests a sliding block 36 slideable between two end abutments 37 and 38. The sliding block 36 is provided with a little notch 39 in which rests the tooth 40 on the corresponding seat of the shaft 27.

In order to ensure the continuity of the contract between each thrust element and the associated tooth 40, on the opposed sides of each seat 31 is provided a peripheral groove 41 and in each groove 41 is positioned a helical spring 42. Each pair of springs 42 is fastened at one of its ends to a cross-member 43, while the other end carries a pin 44 resting against the rear surface of the thrust element 32 urging the sliding block 36 against the corner 40.

A vertical projection 45 is provided in the upper portion of the case 3, and in said projection is positioned a stem 46 carrying a hand wheel 47 and connected by a knuckle 48 to a threaded bolt 49 (FIGS. 1 and 2). The latter is threaded into a nut 50 connected by the stud 51 to a fork 52 carried by the rocking lever 53 the pivot pin 54 of which is capable of sliding in an elongated hole 55 in a member 55a mounted in projection 45. The lower end of the lever 53 is provided with another fork 56 the ends of which are connected by the pins 57 to the bushing

58 mounted on the bearing 59. The latter is mounted on the collar 60 which is provided with the plain bearing 61 through which passes the shaft 1.

The collar 60 is bodily connected to the yoke 62 (FIG. 6) at the ends of which are mounted the two pins 63 slideable in seats 64 provided in the drum 7. The pins 63 terminate in two oblique teeth 65 which are engaged in helical guide grooves 66 provided on the outer periphery of the drum 9.

The device operates as follows:

When the hand wheel 47 (or an analogous control, for instance a hand operated lever) is operated, the rocking lever 53 is caused to rotate about the pivot 54 causing in turn a sliding movement of the bushing 58 and of the collar 60 with the yoke 62 on the shaft 1.

The pins 63 slide in the seats 64 provided in the drum 7, and their teeth 65, guided in the grooves 66, rotate the drum 9 with respect to the drum 7 which, being directly coupled to the shaft 1, rotates with the latter. Summarizing, the operation of the hand wheel 47 has the effect of changing the relative position of the drums 7 and 9 which simultaneously rotate, driven by the shaft 1, to which the driving torque is applied.

The drums 7 and 9 are provided with inner recesses the eccentricities of which are equal, whereby when the positions of the drums is that shown in FIG. 3, the two eccentricities compensate for each other, and the tubular sleeve 11 is thereby perfectly centered and does not rotate about its axis being held by the ring 26. Under these conditions, the output shaft 27 is stationary.

When the relative position of the drums 7 and 9 is changed by the hand wheel 47, the inner circular bore of the drum 9 takes an eccentric position whereby the sleeve 11, driven by the unit of the drums 7 and 9, always with no rotational movement about its axis, moves along a circular translation path, with a radius corresponding to the difference in eccentricity between the drums 7 and 9. In other words, the movement of the sleeve 11 causes its axis to move along a circular path. Assuming that this movement occurs clockwise starting from the position shown in FIG. 7A, a thrust action of the thrust element 32 occurs against the corner 40 of the output shaft 27. The tangential component generated by said action is converted into a sliding movement of the sliding block 36 while the component at right angles to the sliding block 36 causes a rotation of the output shaft 27 through an angular distance corresponding to the stage of active thrust of the considered element, said stage being 72°. Before the presently considered thrust element has completed its active stage, the subsequent thrust element (FIG. 7B) starts operating through a further sector of 72° and so on so that through a complete revolution of the bore 33 of the sleeve 11, the sequential action of the five thrust elements against the respective corners 40 of the output shaft 27 is obtained. The angular speed of rotation of said shaft 27 is determined by the crank arm depending upon the distance of the path of the circular translation movement of the sleeve 11 from the axis of output shaft 27 and increases therefore with the increase of the difference of eccentricity of the drums 7 and 9, and said difference can be changed by the control means 47. Thus the possibility is provided to change gradually the speed from zero up to the maximum speed of the output shaft 27, and said maximum speed of the output shaft being obtained when the teeth 65 of the pins 63 reach the end of the helical guide grooves 66. When the thrust elements 32 are out of their active stage, i.e. are not pressed against the corner 40, the continuity of the contact between the sliding block 36 and the corner 40 is ensured by the springs 42, as aforesaid. Under these conditions, the thrust elements rotate with a slight frictional sliding movement on the inner surface of the sleeve 11.

In order also to obtain from the variator the function of a differential, it will be sufficient to loosen the lock screw 17 and then the hollow hub can also rotate. In this

case it will be possible also to apply a resistant torque to the hub 14 and any change of speed of either of the elements 14 or 27 will have the effect of causing a reverse variation of the speed of the other element, like the conventional type differentials.

The present invention has been illustrated and described in one preferred embodiment, but it is intended that constructive variations may be practically adopted without departing from the scope of the present invention as defined in the appended claims.

I claim:

1. In a mechanically operating continuous speed variator with an input shaft adapted to be connected to a prime mover and having a first cylindrical drum fixed to said shaft and having an internal circular eccentric bore and two opposed longitudinal recesses at the front end thereof, a second drum positioned in said bore and also having a circular eccentric bore with an eccentricity equal to that of said first drum and having helical guide means on its outer surface, a unit comprising in combination an annular sleeve mounted in the bore of said second drum, a collar fixed on said sleeve, an output shaft aligned with said sleeve, a tooth on said output shaft, a hollow hub carrying said output shaft, a double slider coupling connecting said sleeve to said hollow hub and allowing translational movements of said sleeve, hindering rotational movement thereof about its axis, said output shaft having recessed transverse seats therein, a thrust element mounted in each of said transverse seats for transmitting the movement of said annular sleeve to said output shaft, said thrust elements each having a longitudinal groove and two end projections, rollers mounted in said longitudinal grooves, a sliding block slidably supported by said rollers between said end projections and having a notch therein, said seats having peripheral grooves in said output shaft on the sides of the recesses for said seats, helical springs mounted in said grooves, said springs bearing at one end on said output shaft and at other end on said thrust elements, a casing in which the entire unit is mounted, and a lock screw carried by said casing and engageable with said hollow hub for blocking said hollow hub.

2. The combination as claimed in claim 1, in which said thrust elements are bars extending crosswise with respect to said sleeve and mounted within said recesses for the transverse seats in said output shaft, said bars being parallel to one another and equiangularly spaced a distance equal to 360° divided by the number of said bars, said thrust elements converting a circular translational movement of said sleeve into a rotational movement of said output shaft and acting sequentially thereon.

3. The combination as claimed in claim 1, in which said double slider coupling consists of a ring concentrical with said output shaft and having two pairs of notches located on lines at right angles, and two pairs of front dogs, one pair engaging in each groove, one pair of front dogs being on said hollow hub and the other pair on said collar.

4. The combination as claimed in claim 1 and further comprising means for changing the relative position of said two drums, comprising a control hand wheel, a stem on which said hand wheel is mounted, a vertical projection on said case in which said stem is positioned, a threaded bolt, a knuckle connecting said stem to said threaded bolt, a nut fitting onto said threaded bolt, a rocking lever having fork-shaped upper and lower ends, a stud connecting the fork-shaped upper end of said rocking lever to said nut, two plates each having an elongated hole and secured to the vertical projection of said case in positions opposed to one to another, a pivot pin having the ends slidably positioned in said elongated holes of said plates, a bushing, two pins respectively connecting the ends of the fork-shaped lower end of said rocking lever to said bushing, a bearing in which said bushing is mounted, a collar supporting said bearing, a

yoke rigidly connected to said collar, a pin at each end of said yoke and slidably through said two opposed longitudinal recesses at the front end of said cylindrical drum, said guide means on said second drum being helical grooves, the ends of said pins engaging in said helical guide grooves of said second drum, whereby when said control hand wheel is rotated said rocking lever is caused to rock about said pivot pin causing in turn a sliding movement of said bushing and collar with said yoke on said input shaft, and said pins sliding in said opposed longitudinal recesses of said first drum rotate said second drum with respect to said first drum during rotation of said input shaft by means of the ends of said pins engaging in said helical grooves.
